UNITED STATES PATENT OFFICE.

SAMUEL F. VOSE, OF SHAWNEE, OKLAHOMA.

RECTAL-INJECTION APPARATUS.

1,324,862.

Specification of Letters Patent.

Patented Dec. 16, 1919.

Application filed April 3, 1919. Serial No. 287,125.

To all whom it may concern:

Be it known that I, SAMUEL F. VOSE a citizen of the United States, and a resident of Shawnee, Pottawatomie county, and 5 State of Oklahoma, have invented certain new and useful Improvements in Rectal-Injection Apparatus, of which the following is declared to be a full, clear, and exact description.

10 This invention relates to rectal injection apparatus, and its principal object is to provide an apparatus of improved construction and having self contained means for detachably securing it in place to act as a dam 15 or closure to prevent premature ejection of the injected fluid. The apparatus is intended for use in giving injections to horses and other animals. The invention consists in the several novel features hereinafter 20 fully set forth and claimed.

The invention is clearly illustrated in the accompanying drawing, in which:

Figure 1 is a central, longitudinal section through an apparatus embodying a simple 25 form of the present invention; Fig. 2 is a transverse section, taken on line 2—2 of Fig. 1; and, Fig. 3 is a transverse section taken on line 3—3 of Fig. 1.

Referring to said drawing, the reference 30 character 4, designates a nozzle member which also acts as a clamping member and which has secured to it a tubular stem 5, that extends through it and is secured thereto at 6, by soldering or otherwise fastening it 35 thereto. The tube has a projecting portion 7, at one end arranged for attachment to a flexible tubular connection (not shown) which leads to a suitable plunger operated or other injection apparatus. Conveniently, 40 a corrugated attachment member 8, is provided, which has a reduced screw threaded neck 9, that screws into the internally threaded end of the tube extension 7. The other end of the tube 5, projects out through 45 the smaller end of the nozzle member 4, to provide a tip 10, in which is contained a ball or other check valve for preventing back flow through the tube 5. Said valve is here shown as comprising a ball 11, arranged to 50 seat upon a valve seat formed on the end of a bushing 12. A notched bushing 13, secured in the end of the tip 10, prevents the ball from escaping from the end of the tip.

The nozzle member forms one member of 55 muscle clamping means. Associated with

said nozzle member 4, is companion clamping means for clamping the device to the sphincter muscle of the anus and thereby preventing premature ejection of the injected fluid. Said clamping means comprises in addition to the nozzle member 4, a conical clamp member 14, slidably mounted on the tube extension 7, and means for crowding the clamping members upon the sphincter muscle. Said means may comprise 60 a wing nut 15, threaded upon the externally threaded end portion of the tube 7. The clamping member 14, has an elongated neck portion 16, secured to it, which surrounds the tube 7, and affords a handle for the device. The nut 15, may be screwed up against the end of the neck 16, and the clamping member 14 is thereby positively forced toward the conical nozzle member 4, to clamp 65 the sphincter muscle therebetween. 70

To guard against chafing and danger of injury to the animal, and to insure retention of the injected fluid, pliable centrally apertured pads 17, 18, are employed between the clamping members. Said pads are conveniently made of rubber or other pliable material and are removably secured in place on the opposing sides of the clamping members 4, 14. In the form of the invention illustrated, each clamping member 4, 14, has a 80 wall 19, 20, soldered or otherwise secured to it at a place adjacent its larger end, against which the pad is placed. The pads have annular flanges 21, which overhang the edge portions 22, of the clamping members, and 85 are formed with complementary, annular ridges and grooves 23, 24, 25, 26, that facilitate the clamping action of the clamping members. A washer 27, placed against the pad 17, and fastened in place by the tube 90 portion 7, retains the pad 17, upon its seat and a screw threaded nipple 28, threaded in a flange 29, of the wall 20, and having a shoulder 30, bearing against the pad 18, retains the latter in place against the wall. 95 The clamping members 4, 14, are preferably hollow thereby reducing the weight of the apparatus, and the metal parts may be finished in any desirable manner. 100

In use, the nozzle portion 4, is inserted far 105 enough to bring the sphincter muscle between the two pads. The thumb or wing nut 15, is then screwed up against the neck portion 16, of the clamping member 14, thereby forcing the pad 18, against the 110

muscle and clamping it between the pads, thus forming a closure around the tube. The fluid may then be injected through the tube 5, 7, in the usual manner. To remove 5 the instrument, the nut 15, is unscrewed to loosen the pressure upon the muscle, after which the instrument may be withdrawn. It is to be noted that the instrument may be readily taken apart for the purpose of 10 cleaning and sterilizing it.

More or less variation of the exact details of construction is possible without departing from the spirit of this invention; I desire, therefore, not to limit myself to the 15 exact form of construction shown and described, but intend, in the following claims, to point out all of the invention disclosed herein.

I claim as new and desire to secure by 20 Letters Patent:

1. An apparatus of the character described, comprising a fluid injecting tube, a nozzle member stationarily secured to said tube, a companion clamping member slidably mounted on said tube, annular, muscle gripping pads on the opposing faces of the nozzle and clamping members, and means for adjusting said slideable clamping member toward the stationary nozzle member. 25
2. An apparatus of the class described, comprising a fluid injecting tube, a nozzle stationarily secured thereto, an adjustable companion muscle clamping member slidably mounted on said tube and coöperating 30 with said nozzle to clamp a muscle therebetween, annular, pliable pads secured to the opposing sides of said nozzle and adjustable clamping member, and a nut threaded on said tube and arranged to bear against said 35 adjustable clamping member.
3. An apparatus of the class described, comprising a fluid injecting tube having a nozzle member thereon, an adjustable companion muscle clamping member slidably 40 mounted on said tube, opposing annular, muscle gripping pads removably secured to said nozzle and clamping member respec-

tively, and means for adjusting said clamping member toward the nozzle.

4. An apparatus of the class described, 50 comprising a fluid injection tube having a combined nozzle and muscle clamping member thereon, an adjustable muscle clamping member slidably mounted on said tube, pliable pads on the opposing sides of said 55 clamping members, and a nut threaded on said tube and arranged to bear against said adjustable clamping member.

5. An apparatus of the character described, comprising a fluid injection tube 60 having a connection for a flexible tube at one end and a check valve at the other end, a nozzle surrounding said tube at the end containing the check valve, a companion muscle clamping member slidably mounted on said 65 tube and coöperating with said nozzle to clamp a muscle therebetween, pliable pads on the opposing sides of said nozzle and clamping member, and means for adjusting said clamping member toward said nozzle. 70

6. An apparatus of the character described, comprising a fluid injection tube, a nozzle secured thereto at one end and surrounding the same, said nozzle comprising also one member of a muscle clamp, a companion clamp slidably mounted on said tube and having a reduced neck surrounding said tube, annular muscle gripping pads on the opposing sides of said clamp members and means for adjusting one of said members 80 toward the other. 75

7. An apparatus of the character described, comprising a fluid injection tube, and a two part, oppositely tapering muscle clamp on said tube. 85

8. An apparatus of the character described, comprising a fluid injection tube, a two part, oppositely tapering muscle clamping member, pliable pads on the opposing sides of the two parts of said clamping 90 member, and means for adjusting said parts toward each other. 90

SAMUEL F. VOSE.
